United States Patent Office

Des. 217,312
Patented Apr. 21, 1970

217,312

CARD FILE BOX OR THE LIKE

Alice C. Sharon, Rte. 1, Fowler, Colo. 81039

Filed June 29, 1967, Ser. No. 7,646

Term of patent 14 years

Int. Cl. D19—99

U.S. Cl. D74—2

Fig. 1

Fig. 2

Fig. 3

FIG. 1 is a front elevational view of a card file box showing my new design;

FIG. 2 is a side elevational view, the side opposite thereto being a mirror image thereof; and

FIG. 3 is a rear perspective view thereof.

I claim:

The ornamental design for a card file box or the like, substantially as shown and as described.
